UNITED STATES PATENT OFFICE.

ALEXANDER RAY, OF PHILADELPHIA, PENNSYLVANIA, ASSIGNOR TO
EDWARD S. LOWRY, OF PHILADELPHIA, PENNSYLVANIA.

CHUTE-WAGON.

SPECIFICATION forming part of Letters Patent No. 710,611, dated October 7, 1902.

Application filed June 14, 1902. Serial No. 111,729. (No model.)

To all whom it may concern:

Be it known that I, ALEXANDER RAY, of the city and county of Philadelphia, State of Pennsylvania, have invented an Improvement 5 in Chute-Wagons, of which the following is a specification.

My invention has reference to chute-wagons; and it consists of certain improvements fully set forth in the following specification 10 and shown in the accompanying drawings, which form a part thereof.

In cases where the coal or other material is discharged from wagons by means of gravity and the employment of chutes it has been 15 difficult to secure the discharge to a great distance, such as the conveyance of coal from the wagon at the curb to the cellar of a house sitting back from the pavement or across a very wide pavement, because it is practically 20 impossible to elevate the body of the wagon and its load sufficiently high to secure the movement of the coal by gravity. To elevate the body above the running-gear introduces many elements of danger, in that it 25 raises the center of gravity so high as to cause the wagon to upset unless care is taken that it is standing upon proper foundation and not upon an inclined road. Moreover, the use of elevating means for the wagon- 30 body causes great strain and wear and tear upon the wagon as a whole and soon renders it unsuited for use until repaired.

The object of my invention is to overcome the above existing objections, and this I 35 secure by retaining the wagon-body as a fixed element upon the running-gear and elevating the coal or materials from the bottom of the wagon-body to the requisite height by a suitable conveyer and from which it is dis- 40 charged into a chute on sufficient incline to convey the coal or material by gravity to the place of deposit.

In carrying out my invention I provide the body of the wagon with a discharge-gate at 45 the bottom and combine therewith an adjustable conveyer into position and extending from the side of the wagon, so that the conveyer receives the coal or material and conveys it to the chute. The conveyer is prefer- 50 ably jointed, so as to extend laterally from under the body and then upward at its side

to the requisite height to secure the proper fall of the coal or material. The chute is connected with the top of the conveyer, and, being supported on an incline, it conveys the 55 coal or material under the action of gravity. The conveyer is adapted to be positively operated and preferably by hand.

My invention also comprehends many details of construction, which, together with the 60 above features, will be better understood by reference to the accompanying drawings, in which—

Figure 1 is a side elevation of a wagon embodying my improvements. Fig. 2 is a cross-section of the same on line 2 2 with the chute extended in position for discharging the materials. Fig. 3 is a side elevation of a chute and conveyer structure in condensed form. Fig. 4 is a cross-section of same on line 4 4, 70 and Fig. 5 is an end view of the chute.

A is the body of the wagon and may be formed with an inclined bottom A', terminating in a discharge-aperture B, having a controlling-gate b to control the discharge, and 75 which is provided with means extending to the side of the wagon for operating it. This wagon-body A is supported in an elevated position upon the truck-frame C by means of suitable supports D and D' of any convenient 80 construction. The supports D may extend nearly to the middle of the wagon-body, as shown in Fig. 2, whereas the supports D' are preferably corner-pedestals, or may, if de- 85 sired, extend transversely across the free end of the wagon and truck. By this arrangement there are formed apertures O between the wagon-body and the truck-frame on the one hand and between the supports D and pedestals D' on the other, the said openings 90 constituting spaces from which the conveyer and chute may be withdrawn or inserted. The truck-frame C is supported upon wheels in any well-known manner.

Arranged upon the truck-frames C and ex- 95 tending longitudinally under the wagon-body are guides E, which are preferably formed of angle-iron. Arranged upon these guides is the carriage F, of any suitable construction, adapted to be moved upon the guides so as 100 to be brought directly under the discharge-opening B of the body or pushed longitudi-

nally on the guides. Pivoted on the carriage at H is a frame G, which is of sufficient length to extend transversely to a little beyond the side of the wagon-body, as shown in Fig. 2. 5 Jointed to this frame G is a second frame N. These parts G and N are provided with a suitable conveyer I, preferably formed of a flexible material, such as canvas, with transverse slats i and with chains I' at its sides. These 10 chains and conveyers are guided and supported by the lateral projecting guides L and the transverse supports L', of metal, connecting the two sides of the frames G and N. The conveyer I is endless and is guided by a roller J at one end of the frame G and by a roller J' at the distant end of the frame N. It is further guided by a roller K at the hinge between the frames G and N, and this roller is provided with sprocket-teeth K' for driving the 15 chains of the conveyers and may be driven by a crank k or otherwise, as desired. The upper guides L of the frame G, adjacent to the roller K, may be curved, as at l, to properly guide the chains when the conveyer is 20 adjusted, as shown in Fig. 2. When the conveyer is out of use, the parts G N are arranged in alinement, as in Fig. 3, and pushed longitudinally under the wagon-body, as shown in Fig. 1. When arranged for use, they are 25 drawn through the opening O into the position shown in Fig. 2 and are held in that position by links P, connected to the top of the wagon.

M' is a suitable chute of ordinary construction, the parts telescoping. The upper end of the chute M is connected with the free end of the frame N by means of lugs m on the chute and side guides n on the frame N, the upper ends of which are bent so as to sustain 30 the chute M when brought to the position shown in Fig. 2. Any other suitable mode of connection may be had between these two parts M and N, if so desired.

By my invention it is evident that all the objection to lifting heavily-laden wagon-bodies upon the truck-frame is avoided and that the necessary elevation of the coal to travel over the chutes M M' by gravity may be secured by the expedient of the hand-driven elevator. 45 It furthermore provides a clear passage-way under the parts N and M, by which pedestrians may readily pass the wagon during the act of unloading. By my invention the wagon may be arranged parallel to the sidewalk, and 50 thereby discharge sidewise to avoid the possibility of blocking narrow streets.

I do not confine myself to any particular construction of conveyer or elevating devices, as these parts may be made in any convenient 55 and practical manner, the construction shown being merely illustrative of one manner of construction suitable for the purpose. Therefore while I prefer the construction shown I do not limit myself to the details thereof, as 60 they may be modified without departing from the spirit of my invention.

Having now described my invention, what

I claim as new, and desire to secure by Letters Patent, is—

1. In a wagon, the combination of the running-gear and the wagon-body normally supported thereon in any fixed manner having a discharge-opening in the bottom between its ends, with an adjustable conveyer arranged under the wagon-body and adapted to be extended therefrom and the end elevated to lift the coal discharged upon the conveyer from the body, and a gravity conveying-chute adapted to connect with the free end of the conveyer when in use for guiding the coal 75 under the action of gravity to the distant place.

2. In a wagon, the combination of the running-gear and the wagon-body normally supported thereon in any fixed manner and having a discharge-opening in the bottom between its ends, with an adjustable conveyer arranged under the wagon-body and adapted to be extended therefrom and the end elevated for lifting the coal discharged upon the 80 conveyer from the body, a gravity conveying-chute adapted to connect with the free end of the conveyer when in use for guiding the coal under the action of gravity to the distant place, and means for supporting the gravity- 85 chute from the conveyer when the same is in collapsed form for adjustment under the wagon-body during transportation.

3. In a wagon, the combination of a wagon-body having a discharge-opening in the bottom, longitudinal guides under the wagon-body, a jointed conveyer having one part pivoted to the carriage and the other part adapted to be extended obliquely outward and upward beyond the wagon-body at the side, 90 means to support the conveyer in position, and a gravity-acting chute extending from the elevated end of the conveyer.

4. In a wagon, the combination of a wagon-body having a discharge-opening in the bottom, longitudinal guides under the wagon-body, a jointed conveyer having one part pivoted to the carriage and the other part adapted to be extended obliquely outward and upward beyond the wagon-body at the side, 95 means to support the conveyer in position, a gravity-acting chute extending from the elevated end of the conveyer, and hand-operated means adjacent to the jointed part of the conveyer for operating it.

5. In a wagon, the combination of a wagon-body having a discharge-opening in the bottom, a truck-frame upon which the wagon-body is supported so as to form transverse openings between the wagon-body and the 100 truck-frame on the sides and extending beyond the center and nearer to one end than the other, longitudinal guides under the wagon-body, a carriage movable upon the guides, a jointed conveyer having one part pivoted to the carriage and the other part adapted to be extended obliquely through the 105 side openings outward and upward beyond the wagon-body at the side, means to support 110

the conveyer in position, and a gravity-acting chute extending from the elevated end of the conveyer.

6. In a wagon, the combination of a wagon-body having a discharge-opening in the bottom, longitudinal guides under the wagon-body, a carriage movable upon the guides, a jointed conveyer-body having one part pivoted to the carriage and the other part adapted to be extended obliquely outward and upward beyond the wagon-body at the side and having guideways on the sides, means to support the conveyer-body in position, conveyer-chains running in the guideways, a flexible connection between the conveyer-chains provided with transverse slats or projections, rollers to guide the conveyer and sprocket-wheels for driving the chains of the conveyer

and a gravity-acting chute extending from the elevated end of the conveyer-body. ²⁰

7. In a wagon, the combination of a wagon-body having a discharge-opening at the bottom, a laterally and upwardly extending adjustable lifting-conveyer extending from the side of the wagon from a point below the discharge-opening to a considerable elevation above the bottom of the wagon, and a gravity-acting chute leading from the elevated end of the conveyer to the place of discharge. ²⁵

In testimony of which invention I have ³⁰ hereunto set my hand.

ALEXANDER RAY.
